(57) **CLAIM**

An ornamental design for a cabinet, as shown and described.

DESCRIPTION

FIG. 1 is a right front perspective view of the design for a cabinet of the invention

FIG. 2 is a front elevational view of the cabinet of FIG. 1. The ornamental design is not visible in the rear view, top plan view, bottom view or side views; and,

FIG. 3 is an enlarged view of the pattern on the front drawer surfaces of the cabinet of FIG. 1.

The characteristic feature of the ornamental design resides in the use of a pattern on the front drawer surfaces of the cabinet.

The broken lines in the drawings depict parts of the cabinet that form no part of the claimed design.
